TRUSS PAD STRUCTURE

Henry L. Hoffmann, Minneapolis, Minn.

Application November 29, 1954, Serial No. 471,791

3 Claims. (Cl. 128—106)

This invention relates to an improvement in a truss structure and more specifically in the structure for adjustably securing a pad to a truss band, and particularly the hernial pad, whereby a very precise lateral adjustment can be secured. Said adjusting structure represents a substantial advance in the art.

It is an object of this invention to provide a truss comprising a band and a pad whereby said band has a portion disposed into said pad for any desired distance thereof, and means for securing said portion in different positions relative to said pad.

It is another object of this invention to provide a truss comprising a band and a pad, said pad having a passage therein, said passage having an enlarged outer portion and an inner threaded portion, and said band having a threaded portion disposed rotatably in said passage whereby longitudinal adjustment is made by rotation of said pad about said portion, and means for holding said pad from rotation.

It is a more specific object of this invention to provide a truss comprising a band and a pad, said pad having a plate therein having a passage substantially thereacross, said passage having an outer portion polygonal in transverse section, and an inner threaded portion, an end section of said band having a portion polygonal in transverse section and an outer threaded end portion, said section being disposed rotatably in said passage and a sleeve slidable about said polygonal portion disposed in said passage to hold the same in different positions relative to said pad.

These and other objects and advantages of the invention will be fully set forth in the following description made in connection with the accompanying drawings in which like reference characters refer to similar parts throughout the several views and in which:

Fig. 1 is a top plan view of applicant's device;

Fig. 2 is an enlarged view of applicant's device in horizontal section taken on line 2—2 of Fig. 1, as indicated by the arrows;

Fig. 3 is an enlarged view in vertical section taken on line 3—3 of Fig. 2, as indicated by the arrows;

Fig. 4 is an enlarged view in end elevation of a portion of applicant's device taken on line 4—4 of Fig. 2, as indicated by the arrows; and

Fig. 5 is a broken away view in side elevation showing a modification of an end portion of a truss band.

Referring to the drawings, and particularly to Fig. 1, a pad 10 is shown. In the embodiment of the invention as here illustrated, said pad is shown to be of a type commonly known as a hernial pad. As here disclosed, said pad is shown to be generally elliptical in plan and of less thickness than width so as to be plate-like in form. As here disclosed, said pad has an outer layer 10a of soft resilient material, such as foam rubber or sponge rubber. Said pad 10 has an inner portion 10b of sheet material, such as metal or plastic material, and as here disclosed said portion 10b is formed of a pair of layers. Said pad 10 has a passage 11 therein

2

substantially thereacross and as here disclosed the same is formed between the layers of material which form said member 10b. Said passage will be adapted to receive therein an end portion of a truss band. In the embodiment of the invention here disclosed, said passage is shown comprising an outer enlarged portion 11a being square in transverse section and an inner portion 11b interiorly threaded.

A truss band 13 is provided. Any type of the truss bands commonly in use may be adapted for use in connection with said pad 10. As here disclosed, said band 13 has a removable terminal portion 14. Said terminal portion 14 has an offset end portion 14a adapted to be secured to band 13 by a recessed screw 15. The manner of securing said portion 14 to said band 13 does not form a portion of the invention herein.

Said terminal portion 14 has a portion 14b here disclosed as being square in transverse section and having an outer threaded portion 14c. Said portion 14c is adapted to be received in passage 11b. Portion 14b is adapted to be rotatably disposed in portion 11a of passage 11. Movable placed about portion 14b is a sleeve 16. Said sleeve is adapted to be disposed about portion 14b in passage 11a and to fit snugly in said passage to prevent the rotation of said portion 14b in said passage 11a. Said sleeve 16 is provided with a pair of upstanding lugs or ears 16a to provide a holding means for moving said member 16.

In operation, when it is desired to position pad 10 on terminal portion 14, said sleeve 16 will be moved to the left with reference to Fig. 2, to a point adjacent the inner end of said terminal portion 14 so as to be entirely removed from passage 11. The threaded portion 14c of member 14 will be threaded into portion 11b of passage 11 and the polygonal portion 14b of member 14 will have a substantial portion thereof disposed in portion 11a of passage 11. Pad 10 will now be rotated. In accordance with the direction of said rotation, said pad may be moved closer to or farther away from the end of band 13 whereby when said band is in position on a wearer's body, said pad may be precisely adjusted to be positioned directly over the hernial opening. The front portion of said band 13 may be moved sufficiently away from the body to permit the rotation of said pad 10. Thus a very precise adjustment may be secured. When said pad 10 is in its desired position on terminal portion 14, said sleeve 16 will be moved into said passage 11 and will be frictionally held therein to hold said pad 10 from further rotation. Said sleeve 16 is very easily moved into and out of position by the use of fingers only and no tool is required. Said ears 16a will be placed directly against a portion of said pad 10 and thus will in no way disturb the wearer.

Referring to Fig. 5, a broken away portion of a truss band 13' is illustrated in which the terminal portion 14' is integral therewith as compared to terminal portion 14 which is removable from said band 13. Said terminal portion is illustrated as having a portion 14'b polygonal in transverse section and a threaded portion 14'c. The operation will be the same as that set forth above.

Thus it is seen that I have provided a novel and simple structure for properly positioning a truss pad to permit its precise adjustment in accordance with the requirements of a wearer of a truss. Said adjustment is very easily and quickly made without the use of any tools or the loosening or tightening of any screws. Applicant's invention represents a substantial improvement in the art of adjusting and positioning truss pads. Applicant's invention is now in commercial production and has been found to be very successful in use.

It will of course be understood that various changes may be made in the form, details, arrangement and proportions of the parts, without departing from the scope of applicant's invention, which, generally stated, consists in a device capable of carrying out the objects above set forth, in the parts and combination of parts disclosed and defined in the appended claims.

What is claimed is:

1. A truss having in combination, a band and a pad, said pad having a passage therein substantially thereacross having an enlarged outer portion and a threaded inner portion, said band having an end section having a threaded portion disposed in said threaded portion of said passage, and a sleeve slidably disposed on said end section of said band and disposed into said band passage to hold said enlarged portion of said pad from rotation about said end section of said band.
2. A truss having in combination, a band and a pad, said pad having a plate structure therein, said plate structure having a passage therein substantially thereacross, said passage having an enlarged outer portion polygonal in transverse section and an inner threaded portion, said band having an end section having a portion polygonal

in transverse section and a threaded end portion, said end section being disposed rotatably into said passage, and a sleeve slidably disposed on said polygonal portion of said band and positioned in said enlarged portion of said passage to hold said pad from rotation.

3. A truss having in combination, a pad having an inner plate structure, a passage in said plate structure, said passage having an inner threaded portion and an outer enlarged portion polygonal in transverse section, and a band having a threaded end portion disposed in said threaded passage and a portion of said band adjacent said threaded portion of said band being polygonal in transverse section and rotatable in said outer passage and a sleeve disposed on said band and slidably on said last mentioned portion of said band in said outer portion of said passage in said pad to hold said pad in different non-rotatable positions relative to said band.
